UNITED STATES PATENT OFFICE

JOHN C. HALL, OF WHITING, INDIANA

GOLF BAG

Application filed April 21, 1928. Serial No. 271,792.

This invention relates to golf bags in general, and specifically to golf bags which are provided with longitudinal divisional walls to form separate compartments, such as disclosed and claimed in my co-pending application Serial No. 271,791 filed concurrently herewith.

In the conventional golf bags a pocket is provided at the side of the bag and outside thereof to receive a plurality of golf balls. The average golf player usually likes to play with a new ball, particularly in putting on the green, but when teeing off or shooting over a water hazard he usually likes to use an old ball so that if the ball goes into the water and becomes lost his loss is negligible. By having the balls all mixed up in a side pocket he either has to pick out each ball individually or else he has to spill all the balls out on the ground to select the one to be used and replace them in the pocket. In a course which has many hazards, this procedure becomes irritating and monotonous and may even have a bearing on the player's game. Also, the present bags make no provision for holding clothes, such as a sweater or a rain-coat. If the clothes are placed in the bottom of the bag they will interfere with the clubs and even then they will not be adequately protected from the elements; nor is there any means provided for locking the bag to prevent the clothes and balls from being stolen.

In the present invention a watertight compartment is provided in which clothing may be stored and used as desired, and whenever the player requires a different ball all that is necessary is to open the pocket by a mere pull of a link and all the balls are in plain sight and in separate compartments. By arranging the ball pocket within the bag, the outside of the bag is free from protruding parts which greatly enhances its appearance. Then by using the hookless fasteners on the side of the storage compartment access to the clothes and the balls is prevented.

The object of the invention is to provide a pocket arranged within the body of the bag to receive a supply of golf balls which are carried in individual compartments in the pocket.

Another object is to provide a new and novel golf bag which has a compartment for holding golf clubs and a separate compartment for storing clothes and the like which is provided with a watertight cover and which is suitably divided to form separate means for carrying a plurality of golf balls in a part of the compartment and still have ample room remaining for storing and carrying clothing.

And a still further object is to provide simple and novel means for locking the storage compartment to prevent access to either the clothing or the ball pocket.

In the accompanying drawing illustrating a selected embodiment of the invention, the views are as follows:

Fig. 1 is a front elevation of my improved golf bag.

Fig. 2 is a top plan view.

Fig. 3 is a detail elevation showing the ball pocket and the compartment fastening means.

Fig. 4 is a transverse sectional view on the line 4—4 of Fig. 3.

Fig. 5 is a similar view on the line 5—5 of Fig. 3.

Fig. 6 is a detail view of the ball pocket.

Referring to the drawings, 6 designates a golf bag having a top ring or collar 7, a bottom 8 and a cylindrical body or casing 9. The bag is provided with the usual stays 10, a handle 11 and a strap 12.

A vertical divisional wall 13 having fastening ears 14 and 15 is arranged in the bag and forms the compartments 16 and 17. The compartment 16 is relatively narrow to receive golf clubs which may be conveniently arranged about the periphery thereof. The compartment 17 is relatively large to provide ample storage space to receive clothing or other necessary equipment. This construction is described and claimed in the aforesaid co-pending application and forms no part of the present invention except in the combination herein claimed.

A watertight cover 18 is arranged to fit over the top of the compartment 17 and this cover may be fixed to the collar 7 and the wall 100

17, or it may be hinged or made removable as desired.

Arranged within the compartment 17 and below the cover 18 is a pocket 19 which is divided by vertical strips 20 and transverse strips 21 to form individual compartments 22 to receive golf balls 23. The pocket 19 is made of flexible material such as leather and has a turned edge 24 about its periphery to provide means for sewing or otherwise securing the pocket to the bag. The pocket is preferably made in two sections as shown in Figs. 3, 4 and 6, or it may be made in one or any number of sections. The casing 9 is slit at 25 and provides flaps 26 to which a hookless fastener 27 is secured for closing the pocket 19.

The bag is also slit below the ball pocket 19 at 28 and another hookless fastener 29 is fastened to the flaps 30 and in line with the fastener 27 to provide means for closing the lower part of the bag. This construction permits free access to the compartment 17 below the pocket without interfering in any way with the ball pocket 19 or with the fastener 27. The fastener 27 is in closed position when the clip 31 is pulled down, and the fastener 29 is in closed position when the clip 32 is pulled up. When both of the fasteners are in closed position a lock 33 may be inserted through the links 34 on the clips 31 and 32 to prevent operation of either fastener so that access to the pocket and the clothes space below the pocket is prevented.

My invention provides a bag which is neat appearing, which is provided with separate compartments for carrying clubs and wearing apparel which is convenient and permits free access to the ball pocket.

Changes may be made in the form, construction and arrangement of the parts without departing from the spirit of the invention or sacrificing any of the advantages thereof, and I reserve the right to make all such changes as fairly fall within the scope of the following claims.

I claim:

1. A golf bag having a division wall extending the length of the bag to divide the bag into separate compartments, a ball receiving pocket arranged in one of said compartments, independent means on the side of said casing for permitting access to said pocket and to said compartment, a cover for said compartment, and means for locking said independent means together.

2. A golf bag comprising a casing, a division wall in said casing extending the length of the bag to divide a bag into separate compartments, means forming a pocket in one of said compartments, said casing having an opening to permit access to said pocket, a fastener for closing said opening, said casing having an opening below said pocket to

permit access to said compartment, and independent means for closing said last opening.

3. A golf bag comprising a casing, a division wall in said casing and forming separate compartments, means forming a pocket within one of said compartments, said casing having an opening to permit access to said pocket, and having an opening below said pocket to permit access to the compartment, a sliding fastener for each of said openings, said fasteners operating in opposite directions, links on said fasteners, means for locking said links together when both of said fasteners are in closed position, and a cover for said last named compartment.

4. A golf bag comprising a casing, a division wall in said casing and forming independent compartments, means forming a pocket having separate ball receiving recesses and positioned within one of said compartments, a cover for said compartment, means fastened to the side of said casing for permitting access to said pocket, and separate means fastened to the side of said casing for permitting access to said compartment below said pocket.

5. A golf bag comprising a casing, a division wall in said casing and forming independent compartments, a wall forming a pocket having separate ball receiving recesses and arranged within one of said compartments, a cover for said compartment, means fastened to the side of said casing for permitting access to said pocket, separate means fastened to the side of said casing in line with said first mentioned means for permitting access to said compartment below said pocket, and means for locking both of said last named means together.

6. A golf bag comprising a casing, a division wall in said casing and forming two separate compartments, a wall forming a pocket within one of said compartments, flaps in the side of said casing forming an opening to permit access to said pocket flaps in the side of said casing forming an opening in said casing below said pocket and in line with said first mentioned opening to permit access to said compartment, an independent sliding fastener for each of said flaps for closing the openings, said fasteners operating in opposite directions, a lock connecting said fasteners when in closed position, and a cover for the top of said compartment.

7. A golf bag comprising a casing, a collar on said casing, a bottom connected to said casing, a division wall in said casing and forming a club compartment and a storage compartment, a pocket arranged in said storage compartment, division walls in said pocket and forming individual compartments within the pocket, each of said individual compartments adapted to receive a golf ball, flaps forming an opening in the

side of said casing to permit access to said pocket flaps forming an opening in the side of said casing below said pocket and in line with said first opening to permit access to
5 said compartment interlocking members on said flaps, an independent sliding fastener for the members of each of said flaps for closing the openings, said fasteners operating in opposite directions, a single lock connecting said
10 fasteners when in closed position, and a cover for the top of said compartment.

8. A golf bag comprising a casing having a longitudinal opening in its side wall, and a ball receiving pocket member having vertical
15 and transverse members arranged therein and forming a plurality of individual golf ball receiving compartments, said ball receiving pocket member being positioned entirely within said bag adjacent the opening in the
20 side wall thereof with its individual compartments facing said opening.
